UNITED STATES PATENT OFFICE.

WILLARD WALRATH, OF JOHNSTOWN, NEW YORK, ASSIGNOR TO FLORENCE J. RANDALL, OF JOHNSTOWN, NEW YORK.

JUG.

Application filed April 18, 1922. Serial No. 554,581.

To all whom it may concern:

Be it known that I, WILLARD WALRATH, a citizen of the United States, residing at Johnstown, in the county of Fulton and 5 State of New York, have invented new and useful Improvements in Jugs, of which the following is a specification.

This invention relates to jugs.

The object is to provide improvements 10 which may be readily incorporated in the construction of jugs, bottles, cans or other similar containers, whether formed of metal, glass or other material, whereby the entire contents of the container may be 15 poured therefrom with only a slight tilting of the same, a vent being provided to coact with the pouring spout to facilitate such action.

Another object is to provide a jug or 20 similar container which may be cheaply produced from the desired material, and having means for deflecting the flow of the liquid contained therein towards the lowest side thereof when the same is tilted slightly 25 from the horizontal, the outlet orifice or spout being in direct alinement with the same, the top of the jug being inclined towards the diameter which is in alinement with the spout, so as to drain the highest 30 point of the tilted jug and direct the contents to the outlet.

A further object is to provide stoppers or closures for the spout and vent holes, said stoppers being hingedly connected to a 35 metallic clip which may be sprung into engagement with the top of the jug in position to be swung into the openings to close the same, and to be held there with a constant pressure to prevent any leakage, and 40 which may be swung into open position to fully uncover the same and to be held therein during the processes of pouring.

A full and complete understanding of the 45 invention may be obtained from a consideration of the following detailed description, taken in connection with the accompanying drawing forming a part of this specification; it being understood that while the drawing shows a practical form of the 50 invention, the latter is not to be confined to strict conformity therewith, but may be changed or modified, so long as such changes mark no material departure from the salient features of the invention, as specifically 55 pointed out in the appended claims.

In the drawing, in which similar reference characters designate corresponding parts throughout the several figures:

Figure 1 is a side elevation of the improved jug or container;

Figure 2 is a top plan view of the same;

Figure 3 is a transverse, vertical sectional view through the upper portion of the jug;

Figure 4 is a similar view, taken at right angles to Figure 3 and through the vent 65 and spout openings.

Referring to the drawing, there is shown a jug formed of glass, porcelain, pottery or analogous material. The body of the jug 1, as shown, is round in cross section, and 70 may be of any desired diameter and length to secure the desired capacity, the bottom of the jug being preferably flat and of uniform thickness with the sides and top.

The top of the jug comprises two oppositely disposed, curved, or inclined walls 2, extending part way down the opposite sides of the body 1 and terminating at their upper or inner ends at or near the vertical center of the body, and formed with opposed, outstanding flanges 3 providing a transverse ridge or bead at the top of the jug, which extends from one side of the body to a point somewhat beyond the center of the same, where the said ridge or bead 85 merges into a downwardly curved wall 4 which rounds into the opposite wall of the body of the jug, as clearly shown in Figures 1 and 4 of the drawing.

The curved or inclined walls 2 are integrally joined together beneath the curved wall 4, as indicated at 5 in Figure 4, and a transverse, oval-shaped opening 6 is provided through this portion of the joined walls 2, thus providing a convenient handle 7 to be readily grasped by the fingers.

The bead 3, at the end opposite to the handle 7, is rounded outwardly or enlarged, as at 8, and is provided with a tapering orifice or spout 9, the lower and smaller end of which communicates with the interior of the jug and lies exactly flush with the adjacent, interior wall of the same, there being no projection to interrupt the flow of the contents of the bottle during the process 105 of pouring.

The merging together of the upper portions of the curved or inclined walls 2, on the interior of the jug provides an added thickness to the same beneath the bead at 110

- the top, and permits of sufficient length to the orifice or spout 9 to receive and tightly hold a closure plug or stopper for preventing leakage. By thus forming the interior, upper end of the jug, a narrow, rounded groove or gutter 10 is provided which extends from the outer wall of the spout, diametrically across the center of the body and longitudinally beneath the top bead to a point adjacent to the handle opening 6, where the same merges into a curved interior wall spaced from and having the same contour as the lower side of the said handle opening.
- 15 Adjacent to the forward end of the handle opening 6, or to that end nearest to the spout 9, a central orifice 11 is provided extending vertically through the bead, and communicating with the interior of the jug, said orifice 11 having its upper end provided with tapered walls and constituting a vent opening for the purpose of admitting air to the interior of the jug when the spout is open during the process of pouring.
- 20 A metallic clip 12 is mounted on the transverse bead formed by the outstanding flanges 3, and the said clip is provided with integral, downwardly extending side plates 13 terminating at each end, in inwardly directed lips 14 which are adapted to be snapped or sprung beneath the overhanging flanges 3 and lock the clip upon the jug, the side plates 13 of said clip providing ample resiliency for the purpose.
- 25 The front edges of the side plates 13, which are preferably rounded as shown, abut against the adjacent, enlarged, rounded portion of the bead surrounding the spout, while the rear edges of said plates, which are 30 likewise rounded, abut against a shoulder 15 formed in the sides of the body, and the clip 12 is thus prevented from any longitudinal movement on the bead at the top of the jug.
- 35 The clip 12, as clearly shown in Figure 2 of the drawing, is provided with a front tongue 16 formed by continuing the curved front edge of the sides plates 13 into the top plate of the clip, and a rear tongue 17 formed in the same way, and these tongues, like the clip proper which is formed of spring metal, have sufficient resiliency to hug the face of the bead. Each tongue is provided with a transverse slot or opening 18 through which 40 is passed a loop-shaped extension 19 of a circular plate 20, to the lower side of each of which is secured a stopper 21 formed of cork or other suitable material and held to the plate 20 by a central rivet 22. The stopper which fits into the spout is, of course, larger than that adapted to fit into the upper, tapered end of the vent opening, and each hinge element composed of the slots 18 and the loops 19, is adapted, 45 by reason of the resiliency of the tongues 16, to snap the stoppers into their respective openings and to hold the same therein, with constant pressure to prevent any leakage through either of the openings.
- 50 The loops 19 have a rectangular, transverse opening therethrough, as shown, and the ends of the spring tongues 16 beyond the slots 18, which form hinge pintles, are also rectangular in cross section, so that when the stoppers are swung to open or close their respective openings, the walls of said loops 19 are forced to open slightly to permit turning action of the stoppers, and thus provides for the desired snapping or springing effect to hold the said stoppers in either open position (as indicated in dotted lines in Figure 4 of the drawing) or in closed position.
- 55 With both stoppers closed, it will be seen that the construction provides a jug which may be conveniently carried without any danger of spilling the contents of the same, and when it is desired to pour from the same, it is only necessary to snap open the spout stopper and the vent stopper, both 60 of which will remain in an out-of-the-way position while the jug is tilted. There being no interior walls or shoulders to interfere with the flow of the liquid, the same will fall, as the contents are lowered, to the 65 bottom of the jug in line with the spout, the inclined or curved walls 2 at the top of the jug serving to drain the upper portion of the jug and thus facilitating the complete emptying of the contents through the 70 said spout.
- 75 From the foregoing it will be seen that a simple, cheaply manufactured jug has been provided which has a direct flow to the outlet opening, and means for draining 80 the top portion of the same, together with adjustable stopper carrying means, which may be readily applied to glass or earthenware jugs to permit the said stoppers to be held with pressure into their respective 85 openings, or to be maintained in open position to allow a full opening of the pouring spout and the air vent, which permits an inflow of air to compensate for the lowering 90 contents of the jug.
- 95 What is claimed is:—
1. A jug having an outlet opening at one end arranged in line with the wall of the jug, and having its side walls tapered and converging inwardly to a ridge to direct the 100 flow of liquid to said opening, said ridge having a handle formed integral therewith.
  2. A jug having two oppositely disposed inclined walls which converge at the top and 105 terminate in a transverse ridge provided with an opening at the outer end coincident with the wall of the jug.
  3. A jug having two oppositely disposed inclined walls which converge at the top and 110

- terminate in a transverse ridge provided with an opening at the outer end coincident with the wall of the jug, said ridge having a second opening at the other end thereof.
- 5 4. A jug having two oppositely disposed curved, inclined walls which converge at the top and terminate in a transverse ridge, the latter having an opening at the outer end coincident with the wall of the jug and a second opening spaced from the first-mentioned opening, and closures for said openings mounted on the ridge.
- 10 5. A jug having two oppositely disposed curved, inclined walls which converge at the top and terminate in a transverse ridge, the latter having an opening at the outer end coincident with the wall of the jug and a second opening spaced from the first-mentioned opening, a clip engaged with the ridge, and 15 stoppers carried by the clip to close said openings.
- 15 6. A jug having its diametrically opposite side walls converging toward the center at the top to provide a transverse ridge, said ridge having outstanding, longitudinal flanges terminating at one end in an enlargement provided with a spout opening whose outer wall is flush with the wall of the jug, a vent opening spaced from the 20 spout opening, a clip provided with inwardly directed lips to engage beneath the longitudinal flanges to retain the same thereon, and stoppers hinged to the ends of the clip and adapted to be swung into and 25 out of their respective seats in the pouring spout and vent.
- 25 7. A jug having its diagrammatically opposite side walls converging toward the center at the top to provide a transverse ridge, said ridge having outstanding, longitudinal flanges terminating at one end in an enlargement provided with a spout opening whose outer wall is flush with the wall of the jug, and said ridge terminating at the other end 30 in a handle and having a vent hole communicating with the interior of the jug adjacent to the handle, a spring clip adapted to snap around the ridge and provided with inwardly directed lips to engage beneath the 35
- longitudinal flanges to retain the same 50 thereon, and stoppers hinged to the ends of the clip and adapted to be swung into and out of their respective seats in the pouring spout and vent.
- 5 8. A jug having the upper portion of its 55 diametrically opposite side walls converging inwardly to a transverse center line at the top of the jug and there joined together to provide a ridge having overhanging side walls and extending more than half the diameter of the jug, and there formed into a handle having a transverse finger hole, the ridge terminating at its opposite end in an enlargement provided with a spout opening 60 communicating with the interior of the 65 jug and flush with the wall thereof, and having another opening therethrough between the handle and the center of the jug, a spring metal clip provided with end tongues having slots and fitted to the ridge between 70 the terminal enlargement and the handle, and having opposite side walls carrying at their lower edges inwardly directed lips to fit beneath the overhanging side walls and retain the clip in place, and stoppers adjusted to fit the openings and carried by 75 plates having loop shaped extensions engaging the slots in the tongues of the clip to permit closing or opening by the stoppers and maintaining the same in either position 80 by the spring of the tongues.
- 5 9. A jug having its diametrically opposite side walls converging toward the center at the top to provide a transverse ridge, said ridge having outstanding longitudinal 85 flanges terminating at one end in an enlargement provided with an outlet, a clip provided with inwardly-directed lips to engage beneath the longitudinal flanges to retain the clip thereon, and a stopper hinged to the 90 end of the clip and adapted to be swung into and out of stopping relation to the outlet.
- 5 In testimony, that I claim the foregoing as my own, I have hereto affixed my signature.

WILLARD WALRATH.
